Attorney

UNITED STATES PATENT OFFICE.

JAMES M. KNIGHT, OF SAN ANTONIO, TEXAS.

DOOR FASTENER.

Application filed November 8, 1921, Serial No. 513,756. Renewed February 21, 1928.

This invention relates to door securing devices, and more particularly to door securing devices of the portable type, the primary object of the invention being to provide a securing device which may be readily and easily applied to the usual door construction, novel means being provided to contact with the door to retain the door in a closed position.

10 Another object of the invention is to provide a device of this character including a body portion and a movable door engaging section, pivoted means being provided for securing the door engaging section in various 15 positions of adjustment, to adapt the same for use with doors of various thicknesses.

With the foregoing and other objects in view which will appear as the description proceeds, the invention resides in the combination and arrangement of parts and in the details of construction hereinafter described and claimed, it being understood that changes in the precise embodiment of the invention herein disclosed, may be made 25 within the scope of what is claimed, without departing from the spirit of the invention.

Referring to the drawing:—

Figure 1 is a fragmental sectional view of a door and its jamb, disclosing the securing device as applied.

Figure 2 is a plan view of the securing device.

Figure 3 is a sectional view taken on line 3—3 of Figure 2.

35 Referring to the drawing in detail, the reference character 5 designates the body portion of the device, which is formed of any suitable metal and provided with an offset end portion 6, terminating in an extension 7, the offset portion 6 being designed to engage within the usual keeper or latch opening of a door jamb, the extension 7 lying in close engagement with one surface of the jamb.

45 Formed within the body portion 5 and disposed in spaced relation with each other, are the openings 8 formed to receive the pin 9 forming a part of the pivoted latch member 10. This latch member 10 is carried 50 by the movable section 11 which is formed of suitable metal and has inwardly extending portions 12 embracing portions of the

body portion 5 as clearly shown by Figure 3 of the drawing, the structure being such as to permit the section 11 to slide freely over the body portion 5.

Ears 13 are stamped from the body portion of the movable section 11 and provide a support for the latch member 10, which is connected to the ears as by means of the pin 60 14 which is shown as extending through registering openings in the ears and latch member. In order that the latch member may be held in a locking position at all times, a coiled spring 15 is provided, which coiled spring is positioned in a suitable recess formed in the sliding section 11, one end of the coiled spring being positioned to engage under one section of the latch member 10, to normally urge one end of the latch member away from the movable section 11.

70 Formed integral with the member 11, is a flange 16, which is relatively wide and adapted to engage the door associated with the fastening device, the door being indicated by the reference character 17, to illustrate the application of the device. Thus it will be seen that the flange 16 provides an abutment, and when the device is positioned on a door jamb, the flange prevents movement of the door to open the same.

75 It might be further stated that the construction of the fastening device is such that the same may be carried in the satchel, whereby persons traveling may be protected against unauthorized persons entering their rooms.

This latch member is also formed with a thumb engaging portion 18 to facilitate the operation of the device.

Having thus described the invention, what is claimed as new is:—

A door securing device including a body portion formed of a length of sheet metal, said body portion having an offset portion 95 adjacent to one end thereof and having a flange at its end adjacent to the offset portion, said offset portion adapted to be positioned within the keeper of a latch, the flange adapted to engage the door frame adjacent to the keeper opening, said body portion having a plurality of spaced openings, a movable section slidable on the body portion and having a flange at one end 100

thereof and disposed at right angles with respect to the body portion and adapted to engage a door, ears stamped from the movable section, said movable section having an opening, a latch member pivotally supported between the ears and having a pin adapted to extend through the opening of the mov-

able member and into an opening of the body portion to lock the movable member against movement.

In testimony that I claim the foregoing as my own, I have hereto affixed my signature.

JAMES M. KNIGHT.
